UNITED STATES PATENT OFFICE.

PAUL E. CHAMBERLIN, OF THE UNITED STATES MARINE CORPS.

AEROTORPEDO APPLIANCE.

1,004,367.

Specification of Letters Patent. Patented Sept. 26, 1911.

Application filed October 26, 1910. Serial No. 539,224.

To all whom it may concern:

Be it known that I, PAUL E. CHAMBERLIN, a citizen of the United States, and an officer of the United States Marine Corps, have 5 invented certain new and useful Improvements in Aerotorpedo Appliances, of which the following is a specification.

My invention relates to improvements in aero-torpedo appliances.

10 The primary object of the invention is, as indicated, to effect the delivery of a torpedo by aerial means against an object, more particularly a naval war vessel, for securing a vantage position for delivering the torpedo 15 and for insuring certainty of execution, or effectiveness.

The invention consists of certain instrumentalities or features substantially as hereinafter fully disclosed and defined by the 20 appended claims.

In the accompanying drawings, illustrating the preferred embodiment of my invention and wherein various changes or modifications may be made provided the same 25 fall within the scope of the invention, without departing from the spirit of the latter, Figure 1 is a front elevation of my invention. Fig. 2 is a plan view thereof. Fig. 3 is a side elevation of the same, with the 30 blades or planes thereof shown in dotted lines in folded position. Fig. 4 is an enlarged partly sectional and partly side view of the invention. Fig. 5 is a vertical section produced through Fig. 4 upon the line 35 X—X, viewing rearwardly. Fig. 6 is a broken, or fragmentary detailed view, showing more especially the tripping and releasing means for the holding-down or retaining guy lines for the blades or planes. Fig. 40 7 is also a detailed view showing more particularly the tripping means for the pivoted seat-supporting bar or member. Fig. 8 is a detailed rear elevational view, disclosing more especially the safety attachment for 45 the torpedo combination time and percussion fuse, including the locking lever for the plunger for igniting the fulminate or fuse of the torpedo. Fig. 9 is a detailed sectional view taken upon the line y—y of Fig. 50 4, showing more particularly the retaining member and spring for the operator's lever. Figs. 10 and 11 are fragmentary detailed

views of the universal joint connection for the blades or planes.

In carrying out my invention, I employ, 55 in connection therewith for putting the same into execution a mono-plane, as for instance, a modified form of the "Antoinette VII" mono-plane, or any other good type of such machines. I also provide an engine 2 of 60 high power and of light-weight type especially adapted for developing high speed. As the particular use for which the engine is intended in connection with my invention as presently more fully appreciated, is not 65 designed especially for long or extended flights, much weight may be economized in its construction, no cooling apparatus being needed therefor, and little fuel required to be carried thereby.

70 The mono-plane 1 is suitably adapted for carrying, at its forward end, a torpedo 3, preferably formed of armor-steel and heavy enough to pierce the thin sides and decks of naval vessels or ships. It is intended to 75 carry, approximately, 180 pounds of wet gun-cotton and to be supplied with an explosive material, such for instance as what may be termed a combination time and percussion fuse.

A lever 5 for the operator is suitably fulcrumed upon the underside of the platform or board member 6 carrying the operator's seat 7, said lever being disposed within convenient reach of the operator from said seat. 80 Said lever 5 has flexible or cable connection 8 with a spring-actuated lever or latch 9 suitably pivoted at one end and adapted intermediate of its ends, to be engaged with, and lock a plunger 10 in position, as against 85 the ignition of the fulminate or fuse of the torpedo, until said lever is released as presently explained. Said plunger is suitably arranged with relation to the torpedo for 90 effecting the firing thereof as above indicated, being suitably automatically actuated when released or tripped. The lever 5 is initially retained in its full-lined position by the action of a spring 11, effecting connection therebetween and the machine-frame, such retention of said lever being 95 aided by means of a bar 12 suitably fixed in position upon the machine-frame and having a socket or notch 13 receiving said lever,

as disclosed especially by Figs. 4 and 9. This lever also has connection with, and provides for the retention of, the blades or planes of the mono-plane extended, as when in flight as presently seen.

The platform 6 has its forward end suitably pivoted in position as indicated at 6^a in the machine-frame and is upheld in initial or normal position upon a rod-member 13 pivoted at one end as 13^a. The opposite end of the rod-member 13 is engaged or upheld preferably by a curved or arcuate member 14 having one end pivoted to the lower end of an arm 15 preferably sleeved as 15^a upon a rod 17 suitably secured to the machine-frame, the purpose of which will be apparent later.

A bell-crank 18 is pivoted at its angle upon an upward extension of the arm 15 and has one of its arms provided with a cuff 19 adapted to receive the free or outer end of the pivoted member 14 for the retention of the latter initially in the full-lined position more especially indicated in Fig. 7, as when retaining the rod-member 13 in position to uphold the seat-supporting platform 6, in its normal position. The other arm of the bell-crank 18 has inflexible or rod-connection 20 with the operator's lever 5 whereby, it will be noted, that, by suitably releasing the lever 5 from the retaining bar or catch 12 so that the spring 11 shall deliver a reactionary stress upon said lever, the latter will be caused to assume the dotted line position indicated in Fig. 4. The pull thus exerted upon the rod 20 will disengage the bell-crank 18 from the pivoted member 14 which will drop to the indicated dotted line position of Fig. 4, accordingly releasing the rod 18, which will allow the seat-supporting platform to assume the dotted line position of the same figure, together with the seat, thus dropping the operator out of the monoplane and out of line with the torpedo the operator preliminarily directing his machine toward the vessel or object of attack. Simultaneously with this movement of parts the lever 9 will be disengaged by the pull of line 8, from, and allow the plunger 10 to be engaged with, and, by frictional contact, ignite the fulminate or fuse, accordingly resulting in the timely exploding of the torpedo into the object or vessel, at which the torpedo is aimed, *i. e.*, at the instant, about, when it reaches the vessel or object, the life of the fuse being previously predetermined, accordingly providing for the time of ignition with respect to the distance from the vessel or object, thus effecting the piercing and sinking of said object or vessel.

A suitable parachute 22 is suitably stored in the mono-plane, having spring-connection therewith as at 23 for retention in place, which parachute is in practice, adapted to be suitably connected or harnessed to

the operator, to relieve him of the ~~burden~~ 70
ness of the fall which would otherwise re-
sult as the seat supporting platform is
tripped and serve as a means for his flota-
tion. Also simultaneously with this action
of parts the blades or planes 24 of the mono-
plane will be thrown upwardly into the dotted
line position indicated in Fig. 3, out of
effective action, allowing the unobstructed
downward precipitate movement of the de-
vice with the torpedo. This is accomplished
through the following instrumentalities:
An arcuate yoke-like member 25 is suitably
secured to the frame of the machine, near its
forward end, said yoke member having 80
trucks or wheels 26 applied to its lower ends
for readily launching or transporting the
device when required. The blades or planes
24 have universal joint connections 27 with
the mono-plane frame for their suitable up-
wardly and rearwardly folding movement
or action. Each universal joint or connec-
tion comprises a ball or spherical member
28, axially supported in position in a post or
bracket 29 screwed or secured into the ma-
chine-frame, said ball or spherical member
having swiveled thereto, at right-angles to
its axis of movement an arcuate socket mem-
ber 30 having preferably a dovetailed mort-
ice and groove connection 31 with a blade 95
or plane member. A line or flexible connec-
tion 32 is attached to, and is under the con-
trol of the lever 5, said line passing rear-
wardly over suitably arranged pulleys 33
and 33^x, and terminating in branch-lines 34. 100
Said branch-lines also are passed over suit-
ably arranged guide pulleys 35, the ends of
said lines being connected to the outer ends
of eye-ended retainers 36, receiving the free
ends of hook-like members 37, said retainers 105
36 and hook-members 37 being each pivoted
at one end, to each of the legs of said yoke-
like member 25. The retainers 36 are ini-
tially held in engagement with the free ends
of the hook-member 37 by means of springs 110
38 connected to said retainers and said yoke-
member 25. Guy-lines 39 for holding down
the blades 24 of the mono-plane 1, are
looped through links 40, connected to, or re-
ceiving the hook-members 37, the opposite 115
portions or ends of said guy-lines being
suitably connected to said blades at their
outer ends. It will be noted that in order
that these guy-lines may be released, as is
necessary when the blades 24 are upwardly 120
folded out of action, the hook-members 37
are required to be released from the retain-
ers 36, which is effected by the pulling ac-
tion exerted through the lines 32, 34 as the
lever 5 is actuated by the operator it being 125
understood that said blades are allowed to
assume such position when the machine is to
descend, and that the resistance from the
air during such descent will, per force, cause
the planes to yield upwardly and rear- 130

wardly by reason of the universal joint connections as above described.

The foregoing described contrivance it will be appreciated has great merits especially for use in naval warfare particularly as relates to securing a vantage position for delivering torpedoes as has been explained.

I claim:

1. A machine of the character described, including an aerial navigating device, a torpedo carried thereby, means for exploding said torpedo, a pivoted platform carrying a seat, and tripping means for said platform.

2. An aerial navigating device, in combination with a torpedo carried thereby, a torpedo-firing means, means for latching in position the torpedo firing means, a pivoted platform carrying a seat, and a tripping means for said platform.

3. An aerial navigating device, in combination with torpedo-firing means, means for latching in position the torpedo-firing means, means for tilting the operator's seat-carrying platform, and means whereby the blades of the aerial navigating device may be folded for taking the same out of action.

4. An aerial navigating device, in combination with torpedo-latching means, means for releasing said latching means, a pivoted platform carrying a seat, and a lever, together with connections between said lever and the aforesaid parts for tripping said platform.

5. A device of the character described including blades or planes, pivoted hook-members, pivoted retainers receiving the beaks or points of said hook-members, said retainers being resiliently held in engagement with said hook-members, flexible connections for said retainers, actuating means for said flexible connections, flexible connections for said blades, and rings engaging said hook-members, said blade flexible connections engaging said rings.

6. A device of the character described, including a pivoted blade, means for carrying said blade, an operating lever, a pivoted hook-member, a link receiving said hook-member, a guy-line looped through said link, a pivoted retainer having an eye receiving the free end of said hook-member, and a flexible connection between said operating lever and said retainer.

7. A device as described, including an aerial propelled contrivance, a seat-supporting platform therefor, pivoted in position at one end, a supporting member arranged under said platform intermediate its ends and itself pivoted at one end, means for supporting the opposite end of said platform

supporting member, and means for tripping the latter supporting means.

8. A device of the class described, including an aerial propelled contrivance, a seat-supporting platform therefor, pivoted at one end, a rod-member itself pivoted at one end and arranged under said seat-supporting platform, a fixed arm, means for supporting said fixed arm, a second arm pivoted to the aforesaid arm and adapted to form a support for the opposite end of said rod-member, a pivoted bell-crank supported from said arm-supporting means, one arm of said bell-crank having at its free end a cuff receiving or engaging the free end of said pivoted arm, an operating lever, and an inflexible connection between said operating lever and said bell-crank.

9. A device of the character described comprising an aerial propelled contrivance, a tilting seat-supporting platform, and means for tripping said tilting platform, including an operating lever, means effecting connection between said lever and a further member of said tripping means, a retaining or catch bar for said lever and a resilient member for effecting the forcible retention of said lever in contact with said catch-bar.

10. A machine of the character described comprising an aerial device, a torpedo carried thereby, means for controlling the explosion of such torpedo, and means for throwing the sustaining means of the device out of flight and releasing such controlling means when the device is properly directed toward an object.

11. A machine of the character described comprising an aerial device, a torpedo carried thereby designed to explode at a predetermined time, means for throwing the sustaining means of the device out of flight when properly directed toward an object, and means for discharging an operator from the device synchronously with throwing the device out of flight.

12. A machine of the character described comprising an aerial device having foldable wings, a torpedo carried by said device, means for controlling the explosion of such torpedo, and means for folding said wings out of action and releasing such controlling means when the device is properly directed toward an object.

In testimony whereof I affix my signature in presence of two witnesses.

PAUL E. CHAMBERLIN.
